CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear perspective view thereof; and,

FIG. 9 is the front elevation view of FIG. 2 shown in a state of use.

The longer dashed broken lines showing a hand and the shorter dashed broken lines showing portions of a graphical user interface in FIG. 9 are for the purpose of illustrating environment and form no part of the claimed design. The remaining dashed broken lines in the figures illustrate portions of the electronic device that form no part of the claimed design.

1 Claim, 9 Drawing Sheets
